BARN CLEANER

Lewis J. Gerhartz, Chilton, Wis.

Application July 27, 1949, Serial No. 107,079

9 Claims. (Cl. 198—170)

1

This invention relates to improvements in barn cleaners and more particularly to a barn cleaning conveyor and flight construction.

In barn cleaning equipment as heretofore developed, an endless conveyor chain having flights welded or otherwise rigidly fixed to one side thereof is positioned in the barn gutter and is operated to move litter and manure along said gutter to a discharge point. With this type of conveyor, whenever any material in the gutter is contacted by a particular flight and not moved thereby, said flight is slid up and over said material to thereby twist the conveyor chain in the vicinity of said flight. Twisting of the conveyor chain causes the flights adjacent the first mentioned flight to be also raised off of the bottom of the gutter. When the flights are so raised they do not perform a proper scraping or conveying operation.

It is therefore a general object of this invention to provide a conveyor and flight construction for barn cleaners wherein the operation of adjacent flights is not affected by the raising of one of said flights off of the bottom of the barn gutter, or by unevenness of the bottom of said gutter.

A further object of the invention is to provide a conveyor and flight construction of the class described wherein the flights are hingedly connected to the conveyor in a manner to permit swinging movement in a downward direction from their normal operating positions relative to the conveyor and in a manner to prevent relative swinging movement upwardly therefrom.

A further object of the invention is to provide a conveyor and flight construction of the class described wherein the conveyor flights are normally urged by gravity into contact with the gutter bottom, and wherein movement of said flights upwardly from their normal positions causes twisting of said conveyor chain, said upward movement of the flights being resisted by the tendency of the chain to resist twisting motion.

A further object of the invention is to provide a conveyor and flight construction of the class described wherein the flights are pivoted to lugs on the under side of the conveyor chain and wherein said flights project laterally outwardly from said point of connection, thereby leaving the opposite sides of said chain unobstructed whereby it may be engaged by sprockets at either of said sides.

A further object of the invention is to provide a conveyor and flight construction which is strong and durable, which performs an efficient

2

cleaning and conveying operation, which is relatively simple and easy to manufacture, and which is well adapted for the purposes described.

With the above and other objects in view, the invention consists of the improved barn cleaner conveyor and flight construction, and all of its parts and combinations, as set forth in the claims, and all equivalents thereof.

In the drawing accompanying and forming a part of this specification, wherein is shown one complete embodiment of the preferred form of the invention, and wherein the same reference characters indicate the same parts in all of the views:

15 Fig. 1 is a diagrammatic plan view of a barn cleaner of one type to which the invention is applicable;

10 Fig. 2 is an enlarged fragmentary perspective view of the improved conveyor and flight in operation in a barn gutter, parts being broken away;

15 Fig. 3 is a fragmentary plan view of the improved conveyor and one flight;

20 Fig. 4 is a vertical sectional view taken along the line 4—4 of Fig. 3; and

25 Fig. 5 is a vertical sectional view taken along the line 5—5 of Fig. 3.

Referring more particularly to Fig. 1 of the drawing the numeral 10 indicates a barn gutter which may be arranged in substantially a rectangular form, as shown, and which may have sprocket wheels 11 in three corners thereof. At the fourth corner an upwardly inclined pair of chutes or gutters 12 and 13 which form extensions of the gutter 10 and extend exteriorly of the barn. At the upper outer ends of the chutes 12 and 13, a sprocket wheel 14 is rotatably mounted and may be driven from any suitable source, such as an electric motor (not shown). A relatively large sprocket 15 may be rotatably mounted at the juncture of the lower end of the chute 12 and the gutter 10 as shown.

Extending within the gutter 10 and chutes 12 and 13 is an endless conveyor chain 16 which extends around the sprockets 11, 14 and 15 in the manner shown. The chain 16 has pivotally connected thereto, in a manner to be later described, a plurality of spaced flights 17 which extend transversely of the gutter 10 and which normally scrape the bottom thereof. When the driven sprocket 14 is rotated, the chain 16 is moved thereby in the direction indicated, and the flights 17 are moved along the gutter 10 to normally carry therewith any litter or other material which they may contact. As the flights 17 reach

the outer ends of the chute 13, the material conveyed thereby drops off the chute and is discharged. The flights 17 then move with the chain 16 about the sprocket 14 in a manner to be described in detail hereinafter and onto the chute 12, eventually re-entering the gutter 10 for another cycle.

Referring to Figs. 2 to 5 of the drawing, the chain 16 may consist of a plurality of elongated cast links 18 connected together in equally spaced relationship by alternate links made up of pairs of flat bars 19 held together by pins 20 fixed thereto. The chain normally travels in the gutter 10 adjacent one sidewall thereof with the pins 20 extending in a vertical plane and with the flat bars 19 extending in a horizontal plane.

Fixed, as by welding, to the underside of a predetermined number of the lower flat bars 19, and projecting downwardly therefrom are spaced parallel lugs 21 which extend transversely of the bars 19. The lower ends of the lugs 21 are apertured to receive pins 22 which are suitably retained therein. The pins extend longitudinally of the bars 19 and parallel thereto.

A plurality of channel members 23, having a length substantially equal to the width of the gutter 10, are apertured adjacent one end and are pivotally connected to the pins 22 to form conveyor flights. It will be noted from Fig. 4 that the upper surface of the inner end of each of the channel members 23 is in engagement with the under surface of the bar 19 to which it is connected. It will also be noted that the upper surface of the flight extending inwardly beyond the pin 22 is rounded off as at 24. It is apparent, therefore, that the flights can pivot downwardly about the pin 22 in a clockwise direction (as viewed in Fig. 4), but cannot pivot upwardly from their normal position as shown in Fig. 4 without tipping or twisting the chain 16 therewith.

In operation the channel members 23 scrape the bottom of the gutter 10 and are held thereagainst by their own weight. If, however, a flight comes in contact with a quantity of material in the gutter which effectively resists displacement, the flight will tend to ride up over said material as shown in Fig. 2. In moving upwardly, however, the flight causes the chain 16 to be twisted in a counterclockwise direction as viewed in Figs. 2 and 4. This twisting of the chain does not, however, affect the flights which are adjacent the one which has swung upwardly, because said flights are pivotally connected in the novel manner previously described, and continue to be urged by gravity into engagement with the bottom of the gutter, as shown in Fig. 2.

The channel members 23, while being normally urged into engagement with the bottom of the gutter 10 by their own weight, nevertheless require the exertion of a force considerably greater than their own weight in order to be swung upwardly. This is due to the fact that the flights cannot be swung upwardly from their normal positions without causing twisting of the chain 16. The tendency of the chain 16 to resist twisting, plus the force of gravity acting on the pivoted flights, tends to prevent upward movement of any of said flights and provides an efficient scraping action.

Referring to Fig. 1, it will be noted that the outer end 25 of the chute 13 is cut off abruptly at substantially a right angle to the longitudinal axis of said chute, whereas the outer end 26 of the chute 12 is cut at an acute angle with re-

spect to the longitudinal axis of said chute so that there is a clear space therebeyond. As the flights 17 reach the upper outer end 25 of the chute 13 and begin to move around the sprocket 14 with the chain 16, the flights are no longer supported by the chute 13 and therefore swing suddenly downwardly about the pivot pins 22 to assume a substantially vertical position. As the flights 17 swing downwardly in the manner described, any litter which had accumulated on said flights drops off due to the downward swinging action and to the force of gravity. Fig. 1 diagrammatically shows three of the flights 17 in the downwardly swung position adjacent the sprocket 14.

As the vertically hanging flights 17 adjacent the sprocket 14 move toward the chute 12, they engage the angled outer end surface 26 of the chute 12. The outer end surface 26 engages the under side of the vertically hanging flights 17, and as said flights move toward the chute 12, the edge 26 causes said flights to be raised from a vertical position to a substantially horizontal position, pivotally moving said flights about the pins 22. The flights 17 which have been freed of any accumulation of litter by the above described downward swinging movement, then move down along the chute 12 along with the chain 16, and re-enter the gutter 10 for a new conveying and cleaning cycle.

It is apparent, therefore, that the improved conveyor and flight construction not only provides efficient cleaning of the gutter 10 and conveying of the litter out through the chute 13, but it also provides for the automatic cleaning of the improved flights upon reaching the discharge point. No flight cleaning means, other than that which is inherent in the improved flight structure, is necessary in a barn cleaner embodying the improved conveyor and flight construction.

The fact that the lugs 21 project from the under side of the bars 19 makes possible the engagement of the chain 16 from either side. For example, the sprocket 15 can engage one side of the chain 16 and the sprockets 11 and 14 can engage the opposite side thereof.

The improved construction provides a cleaning efficiency which is not possible with conventional conveyors having rigid flights. Because of the hinged connection, the channel members 23 are maintained in scraping contact with the bottom of the gutter 10, even though said gutter bottom is uneven.

Various changes and modifications may be made without departing from the spirit of the invention, and all of such changes are contemplated as may come within the scope of the claims.

What I claim is:

1. In a conveyor for operation in a barn gutter, a chain link having an outer side and having a lower surface; and a conveyor flight pivotally connected to the lower surface of said link and extending transversely outwardly therefrom normally in a plane substantially parallel to said lower surface, a portion of said flight adjacent said pivotal connection being normally positioned in abutment with said link to thereby prevent pivotal movement of said flight upwardly from its normal position relative to said link.

2. In a conveyor for operation in a barn gutter, a chain link having an outer side and having a lower surface; and a conveyor flight pivotally connected to the lower surface of said link and

normally extending transversely outwardly therefrom in a plane substantially parallel to said lower surface, a portion of said flight outwardly of its axis of pivotal movement being normally in abutment with the lower surface of said link to limit upward movement of said flight relative to said links.

3. In a conveyor for operation in a barn gutter, a chain link having an outer side and having a lower surface; and a conveyor flight pivotally connected to the lower surface of said link and extending transversely outwardly therefrom below the plane of said lower surface, a portion of said flight which is outwardly of its axis of pivotal movement being normally in abutment with the lower surface of said link to limit upward movement of said flight relative to said link.

4. In a conveyor for operation in a barn gutter, a chain link having an outer side and having a lower surface; a longitudinally extending pivot pin connected to and spaced below said lower surface; and a conveyor flight pivotally connected at one end to said pivot pin, said flight normally extending transversely outwardly from said pin in a plane substantially parallel to said lower surface, a portion of said flight which is outwardly of and adjacent said pin being normally in abutment with the lower surface of said link to limit upward movement of said flight relative to said link.

5. In a conveyor for operation in a barn gutter, a chain link having an outer side and having a lower surface; a longitudinally extending pivot pin connected to and spaced below said lower surface; and a channel shaped conveyor flight pivotally connected at one end to said pivot pin, said flight normally extending transversely outwardly from said pin in a plane substantially parallel to said lower surface, said flight having its open side facing downwardly and normally having a portion of its upper surface which is outwardly and adjacent said pin in abutment with the lower surface of said link to limit upward movement of said flight relative to said link.

6. In a conveyor for operation in a barn gutter, a chain link having an outer side and having a lower surface; a pair of spaced lugs projecting downwardly from said lower surface; a longitudinally extending pivot pin spaced below said lower surface and carried by said lugs; and a channel shaped conveyor flight pivotally connected at one end to said pivot pin, said flight normally extending transversely outwardly from said pin in a plane substantially parallel to said lower surface, said flight having its open side facing downwardly and having a portion of its upper surface which is outwardly of and adjacent said pin normally in abutment with the lower surface of said link to limit upward movement of said flight relative to said link.

7. In a conveyor for operation in a barn gutter, a chain link having an outer side and having a lower surface; a pair of spaced lugs projecting downwardly from said lower surface; a longitudinally

extending pivot pin spaced below said lower surface and carried by said lugs; and a channel shaped conveyor flight pivotally connected at one end to said pivot pin, said flight normally extending transversely outwardly from said pin below the plane of said lower surface, said flight having its open side facing downwardly and having a portion of its upper surface which is outwardly of and adjacent said pin normally in abutment with the lower surface of said link to limit upward movement of said flight relative to said link.

8. In a conveyor for operation in a barn gutter, a chain link having an outer side and having a lower surface; a pair of spaced lugs projecting downwardly from said lower surface; a longitudinally extending pivot pin spaced below and parallel with said lower surface and carried by said lugs; and a channel shaped conveyor flight pivotally connected at one end to said pivot pin between said lugs, said flight normally extending transversely outwardly from said pin below the plane of said lower surface, said flight having its open side facing downwardly and having a portion of its upper surface which is outwardly of and adjacent said pin normally in abutment with the lower surface of said link to limit upward movement of said flight relative to said link.

9. In a conveyor for operation in a barn gutter, 30 a chain link having an outer side and having a lower surface; a pair of spaced lugs projecting downwardly from said lower surface; a longitudinally extending pivot pin spaced below said lower surface and carried by said lugs; and a channel shaped conveyor flight pivotally connected at one end to said pivot pin, said flight normally extending transversely outwardly from said pin in a plane substantially parallel to said lower surface, said flight having its open side facing downwardly and having a portion of its upper surface which is outwardly of and adjacent said pin normally in abutment with the lower surface of said link to limit upward movement of said flight relative to said link.

40

10. In a conveyor for operation in a barn gutter, 35 a chain link having an outer side and having a lower surface; a pair of spaced lugs projecting downwardly from said lower surface; a longitudinally extending pivot pin spaced below said lower surface and carried by said lugs; and a channel shaped conveyor flight pivotally connected at one end to said pivot pin, said flight normally extending transversely outwardly from said pin in a plane substantially parallel to said lower surface, said flight having its open side facing downwardly and having a portion of its upper surface which is outwardly of and adjacent said pin normally in abutment with the lower surface of said link to limit upward movement of said flight relative to said link.
